UNITED STATES PATENT OFFICE.

EDWIN A. WOOD, OF UTICA, NEW YORK.

GRATE.

SPECIFICATION forming part of Letters Patent No. 233,652, dated October 26, 1880.

Application filed August 30, 1880. (No model.)

To all whom it may concern:

Be it known that I, EDWIN A. WOOD, of Utica, in the county of Oneida, in the State of New York, have invented a new and useful Improvement in Grates, of which the following is a specification, reference being had to the accompanying drawings, in which—

Figure 1 is a view in perspective, and Fig. 2 is a vertical sectional view from left to right in front of the trunnions of Fig. 1. Fig. 3 is a sectional view on the line *x x* of Fig. 2, showing the points of support of the central grate. Fig. 4 is a plan view of the bottom of the annular ring.

The object of my invention is to provide a grate for stoves, furnaces, &c., which can be easily and speedily freed from ashes and clinkers from center to circumference.

My invention consists in certain devices, hereinafter more fully set forth, for reciprocating the external ring simultaneously with the turning or oscillating of the central portion or main grate upon its trunnions, whereby the ashes and cinders are loosened from the center to the circumference of the grate, and are by the same operation deposited in the ash box or pit.

Referring to the drawings, A designates the base of the furnace, in which the ring D is supported by means of trunnions E. The annular portion or ring D is provided with radial projections or bars *c*, which incline downward toward the central portion or grate F. The annular portion or ring D supports, by means of a series or number of lugs or projections, *a*, an outer ring, B, said ring being provided with a projecting flange, *a'*, by which it is supported on the lugs or projections *a* of the ring D. These lugs or projections *a* are of sufficient length to permit of an annular space or air-passage, *b*, between the outer and inner rings. The outer ring, B, is provided on a portion of its lower edge with teeth C, which mesh into a segmental pinion on the main grate shaft or arm, as hereinafter more fully explained.

F is the main grate, made in oval form in horizontal section, as shown, so as to project upward into the body of the furnace. This form of grate, which I am aware is not new, prevents the accumulation of ashes at the cen-

ter of the grate, secures a more extended grate-surface, and insures a more thorough circulation of air up into the body of the furnace or fire-chamber. The rear end of the grate F is provided with a trunnion, which fits into a hole or bearing, D', in the inner ring, D, as shown in Fig. 3. The outer end of the grate F is provided with an extended arm, *g*, by which this end is supported, by a staple, *i*, or other suitable device, to the top of the ash-box or base. The arm or trunnion *g* is also provided with a segmental pinion, G, which meshes into the teeth C on the under side of the outer ring, B, so that when the grate F is turned or oscillated by means of a crank or wrench, *k*, applied to the outer end of arm or trunnion *g*, the outer ring, B, will be horizontally reciprocated simultaneously with the vertical oscillation of the grate F.

To prevent the displacement or working up of the outer ring, B, two or more lugs or brackets, *h*, are bolted or cast thereon, which project inward so as to come under the lower edge of the inner ring, D.

When the grate is to be cleaned or freed from ashes or clinkers, by the turning or rocking to and fro of the crank or wrench on the end of the arm *g* the center grate, F, is turned or rocked on its trunnions, and at the same time the outer ring, B, is reciprocated, thus forcing or directing the ashes and clinkers downward, owing to the inclination of the projections or bars *c* on the inner ring into the angle between the rings and the grate F, from which point they are discharged into the ash box or pit.

A projecting arm, *k*, (see Fig. 4,) is cast on the stationary ring D, which, when the grate is in position, comes just under the roof or top of the ash-pit mouth, and prevents both ring D and central grate, F, from rising.

I am aware that it is not new to construct grates with convex surfaces.

I am also aware that grates having a reciprocating ring and an oscillating concavo-convex grate have been combined; but in such cases the two motions of reciprocation and oscillation have not been simultaneous.

Having thus fully described my invention, what I claim, and desire to secure by Letters Patent, is—

1. In a grate for stoves, furnaces, &c., a vertically-oscillating grate, and a horizontally-reciprocating ring, arranged and combined as shown and described, whereby a joint and simultaneous action of the grate and ring is obtained by one and the same crank or operating device, as set forth.

2. The combination of the fixed inner ring, D, and the oscillating grate F, mounted or secured therein as described, with the segmen-

tal pinion G and outer movable ring, B, provided with the teeth or rack C, whereby the outer ring, B, is given a reciprocating motion and the grate F a simultaneously oscillating motion, as set forth.

EDWIN A. WOOD.
